In this example, the two sets of data are not perfectly aligned. The first set of data points (red circles) are shifted to the right relative to the second set (blue squares). The regression line is drawn through the blue squares, showing a positive slope. The residuals are the vertical distances between the data points and the line, with the red circles generally having larger residuals than the blue squares.

a safety pin; a flat member folded around a limb of the pin to form two plies, said plies being connected together adjacent the pin and being also connected together intermediate their first-mentioned connection and their free ends; cooperating fastening means carried by said plies adjacent their free ends for detachably connecting said free ends together.

In testimony whereof I have hereunto set my hand at Grand Rapids, Michigan, this 19th day of November, 1923.
